J. W. RYAN

GILL BOX OR FRAME

Filed Oct. 23. 1922

Inventor

John William Ryan
by Right of Crown Linley Mary
Atteys.

UNITED STATES PATENT OFFICE.

JOHN WILLIAM RYAN, OF LEEDS, ENGLAND, ASSIGNOR TO FAIRBAIRN LAWSON COMBE BARBOUR LIMITED, OF LEEDS, YORK, ENGLAND.

GILL BOX OR FRAME.

Application filed October 23, 1922. Serial No. 596,485.

To all whom it may concern:

Be it known that I, JOHN WILLIAM RYAN, residing at Gledhow Mount, Harehills Lane, Leeds, in the county of York, England, have 5 invented a new and useful Improvement in Gill Boxes or Frames, of which the following is a specification.

This invention relates to gill boxes and like machines used in the treatment of 10 fibrous substances of that class of said machines wherein the gilling members or fallers are actuated by rotary screws. In this type or class of machine the fallers extend from 15 side to side thereof to engage with their operating screws, the upper pair of which carry said fallers to travel over guiding bars until the ends of their paths are reached on 20 which, by cam action, they are forced down and fall from the position upon the upper guiding bars down into position upon the lower guiding bars in which position they engage with the lower pair of screws which return them to their initial positions.

This falling of the metal bars or fallers 25 from their higher to their lower positions causes great deterioration as well as damage due to jamming or other defective actions. In accordance with my invention, to obviate these defects I make use of devices which 30 will receive each faller under resilient action in a horizontal direction and also in its vertical descent so that the sudden arresting and free fall of the faller are entirely 35 prevented and all concussions and deleterious forces are eliminated thus preventing excessive wear and abrasion of those parts that have heretofore been found to be most liable to such actions. The said devices also are capable of adjustment to meet any slight 40 alterations or abrasions that may occur, by which means the operating parts may at all times be readily adjusted and kept in proper working order.

In the accompanying sheet of drawings 45 which illustrates my invention,

Fig. 1 is a sectional side elevation of sufficient of a gill box or gill frame with the operating screws in position thereon to show the application of my improved parts.

50 Fig. 2 is an end elevation showing the parts as seen looking from left to right of Fig. 1.

Fig. 3 is a plan of certain of the parts shown by Fig. 1.

55 To attain the object of my invention I

make use of two buffer springs 2 which are mounted at the end of the faller's path over the upper guides 6, one of said springs being situated on one side of the machine while the other is situated on the other side thereof in known manner. Only one of such springs is shown in the accompanying drawings the other being on the opposite side of the machine. These springs 2 extend in positions vertically adjacent to the ends *a b* 60 of the screws 3 and 4 to receive the fallers 5 as these latter travel in their horizontal paths over the upper guiding bars 6, and said springs 2 are so shaped that each of them may be fixed to the outer ends of levers 70 65 which are pivoted beneath or lower than the guides or slides 6 and 8 which conduct or guide the fallers 5 through their upper and lower horizontal paths of motion respectively.

75 Each of the these levers 7 is pivoted at *d* near the end upon which the spring 2 is fixed and each of said levers 7 is arranged to extend horizontally adjacent the lower screw 4 so that its outer end *7a* may have 80 mounted upon it an eye-bolt 9 which is provided with check nut adjustments *f, g* and connected at *h* to a lever 10. The connections of the check nuts and pivoted bolt are of such character as will enable slight oscillations of the lever and its bolt without binding action.

85 The lever 10 (one being situated on each side of the machine) is pivoted at *k* upon bearings 11 which are beyond the pivot *h*, 90 so that an extension *10a* of the lever 10 may have mounted upon it a counterbalancing weight 12, this weight 12 being adjustable so that it may be regulated for purposes 95 hereinafter explained. The levers 10 on each side of the machine extend into proximity to the ends *d* of the levers 7 or into alignment with the path through which the fallers 5 travel when moving or descending from engagement with the screws 3 to their 100 engagement with the screws 4.

105 Upon the said extending ends of these levers 10 are mounted pivoted rods 13 which extend through and slide within guiding slides 14 at each side of the machine so that the upper ends of these rods 13 may operate or move in the vertical paths which the fallers follow when descending as before described.

110 By this arrangement of the devices on

each side of the machine the resilient buffer springs 2 with which each faller 5 comes into contact at the end of its upper horizontal path when travelling over the guiding bars 6, act as yielding buffers during the said short portion of the horizontal movements of said fallers, while when the screws 3 operating said fallers continue to move the same horizontally causing the said springs 10 2 to raise the extending ends 7^a of the levers 7 so that these levers will raise (by their eye-bolts 9) the arms of the levers 10 and also the sliding bolts 13 to bring them into their raised position to receive the fallers 15 5 thereon. When the fallers have thus reached a position over the upper ends of the vertical rods 13 the cams which operate and force down said fallers in well known manner, cause the rods 13, which are counterbalanced by the weights 12, to move downward and the fallers are carried from the plane of their upper path to that of their lower path under conditions that eliminate all the concussions and therefore reduce to a minimum the liability of wear in 20 any of the parts.

The buffer springs 2 are fixed upon the ends of the levers 7 by a kind of dove-tailed joint being formed on the spring for the 30 end of the lever 7 to take into so that the actions of the fallers thereon will not cause any breakages as said fixing and holding of the springs will not entirely depend upon the tensile strength of the screws 8 for over- 35 coming the forces encountered.

Such being the nature and object of my said invention what I claim is:—

1. In a gill box or frame, the combination with upper and lower horizontal faller 40 guides, faller bars, and screws adapted to move said bars along the guides, of a yielding arm extending into the path of the faller bars as they are successively forced from the upper guide, and means connected 45 with said arm for receiving the bar as it leaves the upper guide and supporting it while moving downward to the plane of the lower guide.

2. In a gill box or frame, the combination with upper and lower horizontal faller 50 guides, faller bars, and screws adapted to move said bars along the guides, of a lever mounted below and extending beyond one end of said screws, a spring arm attached 55 to the lever and extending upward into the path of the faller bars as they are successively pushed from the upper guide by the co-operating screw, a second lever provided

with means to receive the faller bar forced from the end of the upper guide by the 60 screw and to support the same while it is moving downward to the plane of the lower guide, and means connecting said levers.

3. In a gill box or frame, the combination with upper and lower horizontal faller 65 guides, faller bars, and screws adapted to move said bars along the guides, of a lever mounted below and extending longitudinally of the screws, a yielding arm attached to the lever and extending upward into the 70 path of the faller bars as they are successively pushed from the upper guide by the co-operating screw, said lever being rocked about its fulcrum by pressure exerted on the arm by the faller bar passing from the 75 upper guide, and a vertically reciprocating member connected to the lever and adapted to receive the faller bar at the end of the upper guide and support the same while moving downward to the plane of the lower 80 guide.

4. In a gill box or frame, the combination with upper and lower horizontal faller 85 guides, faller bars, and screws adapted to move said bars along the guides, of a yielding arm extending into the path of the faller bars as they are successively forced from the upper guide, a counter-balanced lever having on one arm means for receiving the faller bar forced from the upper guide 90 and supporting it while moving downward to the plane of the lower guide, and connections between the yielding arm and said lever whereby lateral pressure of the faller bar forced from the upper guide acts to position the support in the plane of said guide. 95

5. In a gill box or frame, the combination with upper and lower horizontal faller 100 guides, faller bars, and screws adapted to move said bars along the guides, of a lever arranged below the screws, a yielding arm attached to the lever and extending upward into the path of the faller bars as they are successively pushed from the upper guide by the co-operating screw, a second lever adjustably connected to the first 105 said lever and having on one arm an upwardly projecting member adapted to be positioned to receive the bar forced from the upper guide by the screw and to support said bar while it is moving downward to the plane of the lower guide, and an adjustable counter-balance on the other arm of the second lever.

JOHN WILLIAM RYAN.
